COMBINED EYESHADE AND CLIP-ON SUNGASSES

Anthony Shindler, Brookline, Mass., assignor to American Optical Corporation, Southbridge, Mass., a corporation of Delaware

Filed June 20, 1968, Ser. No. 12,451

Term of patent 14 years

Int. Cl. D16—08

U.S. Cl. D57—1

FIG. 1 is a perspective view of combined eyeshade and clip-on sunglasses showing my new design;

FIG. 2 is a front elevational view thereof;

FIG. 3 is a rear elevational view thereof;

FIG. 4 is a top plan view thereof; and

FIG. 5 is a side elevational view thereof.

I claim:

The ornamental design for combined eyeshade and clip-on sunglasses, substantially as shown.
